CLAIM

The ornamental design for a trinket, as shown and described.

DESCRIPTION

FIG. 1 is a bottom perspective view of a trinket with removed base; and,

FIG. 2 is a front perspective view of the trinket.

The designs are trinkets for advertising in the form of pumpkins with magnetic bases; the variants include pumpkins with "carved" scared faces; in some variants the pumpkin trinkets are empty and their bases can be removed, creating a small storage space inside.
